US0D1009399S

(12) **United States Design Patent** (10) **Patent No.:** **US D1,009,399 S**
(45) **Date of Patent:** **** Dec. 26, 2023**

(54) **FLUID CONTROL DEVICE**

(71) Applicant: **Transportation IP Holdings, LLC**,
Norwalk, CT (US)

(72) Inventors: **Mark Murphy**, Erie, PA (US); **Jain Raj Vettuvazhy Puthenpurayil**,
Bengaluru (IN); **Rajendra Yammanuru**, Bengaluru (IN);
Theodore Brown, Ripley, NY (US)

(73) Assignee: **Transportation IP Holdings, LLC**,
Norwalk, CT (US)

(**) Term: **15 Years**

(21) Appl. No.: **29/800,300**

(22) Filed: **Jul. 20, 2021**

(51) LOC (14) Cl. **13-03**

(52) U.S. Cl.

USPC **D13/179**

(58) **Field of Classification Search**

USPC D34/28; D13/179
CPC .. F28F 19/01; F28F 2210/02; F28F 2250/102;
H01L 23/3672

(57) **CLAIM**

The ornamental design for a fluid control device, as shown and described.

DESCRIPTION

FIG. 1 is a perspective first side view of a fluid control device, showing my new design;

FIG. 2 is a perspective second side view thereof;

FIG. 3 is a first side elevational view thereof;

FIG. 4 is a second side elevational view thereof;

FIG. 5 is a third side elevational view thereof;

FIG. 6 is a bottom plan view thereof; and,

FIG. 7 is a top plan view thereof.

The broken lines in the drawings depict portions of the fluid control device that form no part of the claimed design.

1 Claim, 6 Drawing Sheets
